UNITED STATES PATENT OFFICE

JOHN HULL WHITCOMB, OF LAKewood, AND NORMAN V. WAGNER, OF ROCKY RIVER, OHIO, ASSIGNORS TO THE B. F. GOODRICH COMPANY, OF NEW YORK, N. Y., A CORPORATION OF NEW YORK

DESIGN FOR A HOT WATER BOTTLE

Application filed April 30, 1932. Serial No. 43,680. Term of patent 3½ years.

To all whom it may concern:

Be it known that we, JOHN HULL WHITCOMB, a citizen of the United States, residing at Lakewood, in the county of Cuyahoga and State of Ohio, and NORMAN V. WAGNER, a citizen of the United States residing at Rocky River, in the county of Cuyahoga and State of Ohio, have invented a new, original, and ornamental Design for a Hot Water Bottle, of which the following is a specification, reference being had to the accompanying drawing, forming a part thereof.

The accompanying drawing shows a side elevation of a hot water bottle embodying our new design, the reverse side of the bottle being plain.

We claim:

The ornamental design for a hot water bottle as shown and described.

JOHN HULL WHITCOMB.
NORMAN V. WAGNER.
